UNITED STATES PATENT OFFICE.

CHARLES H. SMOOT, OF MAPLEWOOD, NEW JERSEY.

FURNACE REGULATION.

Application filed December 16, 1926. Serial No. 155,232.

This invention relates to the art of furnace regulation and more generally to the art of regulation by proportionate pressures.

One purpose of my invention is to devise 5 novel apparatus adapted to regulate the resistance offered to the gaseous flow through a furnace to thereby effect the control of the pressure above the fuel bed.

Another purpose of my invention is to 10 devise a complete system for automatic furnace regulation, and adjustable apparatus therefor, embodying the general features of centralized regulation disclosed and described in my Patent No. 1,551,272, granted August 15, 1925, an application, Ser. No. 143,309 for a reissue of which is now pending.

Still another purpose of my invention is to utilize the air pressure from the common forced draft air duct of a boiler plant as a 20 master controlling force for the centralized regulation of the plant.

Other purposes and novel features will become apparent from the description and accompanying drawings.

In the claims annexed hereto I have not included certain of the broad features of my proportionate pressure apparatus hereinafter to be described as these features form part of the invention described in my co-pending 30 application, Serial No. 155,231 filed December 16, 1926, and are therein broadly claimed.

For a better understanding of my invention and the advantages pertaining thereto, reference may be had to the accompanying drawings.

Fig. 1 is a diagrammatic representation of a simple embodiment of my invention.

Fig. 2 is a diagrammatic representation of my invention as applied to the centralized 40 regulation of a boiler plant.

In Fig. 1 I have illustrated my apparatus for maintaining constant the resistance offered by the fuel bed and inlet damper of a furnace to the gaseous flow therethrough. A 45 boiler furnace, 1, having a fuel bed 2, and a stack 3 is supplied with forced draft from the blower 4 through the inlet 5. A damper 6 controls the inlet air flow and a hand operated damper 7 controls the flow of exhaust 50 gases from the furnace. The operation of the damper 7 is immaterial to the embodiment of my invention disclosed in Fig. 1, and might be controlled automatically by the steam pressure or in any other well known manner as desired. The damper 6 is controlled 55 according to my invention by the

apparatus hereinafter to be described. A conduit 8 having the manually operated reducing valves 9 and 10 leads from a point 11 located between the damper 6 and blower 4 60 in the inlet 5 to a point 12 within the furnace 1 and above the fuel bed 2. A conduit 13 leads from the conduit 8 at a point intermediate the valves 9 and 10 to a chamber 14. The chamber 14 is closed by a diaphragm 15 65 to which is rigidly attached a rod 16. The damper 6 and rod 16 are operatively connected by link 17.

With a constant air pressure delivered by the blower 4, this apparatus operates to maintain constant the total resistance offered by the inlet damper and the fuel bed to the air flow through the furnace, and therefore to maintain a constant pressure above the fuel bed according to the following theory.

During combustion there will be a flow of air through the furnace, and a consequent drop in static pressure along the path of flow. The conduit 8 permits a by-path flow from the point 11 below the inlet damper to the 80 point 12 above the fuel bed, which flow, for any definite position of the valves 9 and 10 bears a definite relation to the flow through the furnace between the same two points. The static pressure within the conduit 13 and 85 chamber 14 will be of course intermediate the pressures at the points 11 and 12, its value relative to either of those at these two points depending upon the resistance to the flow through the conduit 8 offered by the valves 90 9 and 10. With the valve 9 partly closed, and thereby offering relatively large resistance, and with the valve 10 wide open and thereby offering relatively small resistance, the pressure within the chamber 14 will have a 95 value closer to that at the point 12 than to that at the point 11. Conversely, with the valve 9 open and the valve 10 partly closed the pressure within the chamber will be nearer that at 11 than that at 12.

For any given inlet air pressure the pressure at the point 12 will depend upon the thickness of the fuel bed and upon the setting of the inlet damper. The opposing pressures of the air within the chamber 14 and of the atmosphere act upon 105 the diaphragm 15 to control the setting of the damper 6 by means of rod 16 and link 17, a departure from atmospheric pressure within the chamber tending to change the position of the damper to return the pressure within the 110 conduit to that of the atmosphere. If the pressure within the chamber 14 increases the

damper is moved to offer greater resistance to the air flow which results in a greater negative pressure at the point 12 and a corresponding decrease in the absolute pressure upon the diaphragm 15. Similarly a decrease in the pressure within the chamber 14 tends to open the damper 6 which results in a decrease in the negative pressure at 12 and a corresponding pressure increase within the chamber 14. 10 With, then, the system in equilibrium, that is, with atmospheric pressure within the chamber 14, there will be a definite negative pressure above the fuel bed at the point 12 and the fuel bed and inlet damper will offer a 15 definite resistance to the flow through the furnace. If now, the fuel bed becomes thin, or holes develop, the resistance offered by the bed will decrease, and the negative pressure at 12 therefore will momentarily decrease and the pressure in the conduit 13 and chamber 14 will exceed that of the atmosphere. This pressure increase will immediately move the damper to increase its resistance until the pressure at 12 returns to its original 20 value and the pressure within the chamber 14 returns to that of the atmosphere. It follows therefore that the resistance added by the new position of the damper must be exactly equal to the decrease in that of the fuel bed resistance. Similarly an increase in the thickness of the fuel bed momentarily increases the negative pressure at the point 12 and decreases that within the chamber 14 which latter moves the damper to offer less 25 resistance to flow to return the pressure at 12 to its original value and to return the pressure within the chamber to that of the atmosphere, the decrease in resistance offered by the new position of the damper being equal 30 to the increase in resistance offered by the thicker fuel bed.

For a given inlet air pressure the valves 9 and 10 are set according to the pressure it is desired to maintain at the point 12 above the bed. A partial closure of the valve 9, with the valve 10 open, will adjust the apparatus to maintain a relatively small negative pressure above the fuel bed, while a partial closure of the valve 10 with the valve 9 open will maintain a larger negative pressure above the bed. 45

Whenever the inlet air pressure changes to a new value the apparatus of Fig. 1 operates to maintain a new pressure above the fuel bed and a new total resistance to flow between the points 11 and 12. If the inlet pressure increases the pressure within the chamber 14 increases causing the damper 6 to increase its resistance to the flow until the pressure within the chamber returns to atmospheric. 50 This can only occur when the negative pressure at 12 has been increased by an amount proportional to the positive pressure increase at 11. The apparatus then operates to maintain constant the new and greater value of the total resistance offered by the damper and

the fuel bed. Similarly a decrease in the pressure at 11 results in an opening of the damper 6 and a proportional decrease in the negative pressure at 12 with a correspondingly smaller total resistance between the 70 points 11 and 12.

Fig. 1 therefore illustrates simple and efficient apparatus for controlling the inlet damper to maintain any desired negative pressure above the fuel bed. The apparatus 75 described permits of ready adjustment if desired, and can be used with or without other regulating devices for the different elements of combustion in the furnace.

In Fig. 2 I have illustrated diagrammatically my system of proportionate pressure regulation as applied to the entire combustion regulation of a plant comprising a plurality of boilers. The numeral 1 indicates one of a series of boiler furnaces supplying 80 steam to the common header 64. Air is supplied to the boilers from the main 65 fed by the blower 4. A damper 6 in the air inlet 5 to the furnace 1 controls the passage of air to the fuel bed 2 and a damper 7 in the stack 90 3 controls the outlet of the gases of combustion. Fuel is fed to the furnace from the hopper 66 by the stoker engine 67. The air main 65 supplies air to a master controller 68 through the pipe 69 provided with the 95 valve 69^a. The pipe 69 connects with the air duct 65 at a point 63 between the blower 4 and the furnaces 1. There are three conduits 70, 71 and 72, leading from the master controller and terminating in branches to the 100 various elements to be controlled through each of which conduits and branches there will be a flow of air controlled by a reducing valve 73. Gauges 18 indicate the pressures in the conduits 70, 71 and 72 beyond 105 the valves 73. A gauge 18^a indicates the pressure in the conduit 69 between the valve 69^a and the main 65, and a gauge 18^b indicates the pressure in the master controller. A branch conduit 19 provided with a valve 20 110 leads from the conduit 70 to a point 21 in the gas flow beyond the boiler tubes 22 of each boiler-furnace. Connected to the conduit 19 between the valve 20 and the conduit 70 is a branch 23 terminating in a chamber 24 closed 115 by a diaphragm 25 which is responsive to the difference between the pressure within the chamber and that of the atmosphere. The position of the diaphragm 25 controls the position of the damper 7 by means of the rod 120 26 rigidly attached to the diaphragm 25, the lever 27 pivoted at 28 and the links 29 and 30, a slight increase in the pressure within the chamber 24 tending to slightly open the damper 7.

A branch 31 provided with a valve 32 leads from the conduit 71 to a point 33 between the tubes 22 and the fuel bed 2 of each boiler furnace. Connected to the conduit 31 between the valve 32 and the conduit 71 is a 130

branch 34 terminating in a chamber 35 closed by a diaphragm 36 which is responsive to the difference between the pressure within the chamber 35 and that of the atmosphere. As shown the diaphragm 36 controls the position of the damper 6 in the same way as the diaphragm 25 controls the damper 7, except that an increase in the pressure within the chamber 35 tends to close rather than to open the damper.

A suction fan 37 is driven by the stoker 11 to run at a speed proportional to that of the stoker. This fan creates a negative pressure at a point 38, which pressure varies inversely with the square of the fan speed, and therefore inversely with the square of the stoker speed. A branch 39 provided with the valve 40 leads from the conduit 72 to this point of negative pressure 38 of the fan 37. Connected to the conduit 39 between the valve 40 and the conduit 72 is a branch 41 terminating in the chamber 42 closed by the diaphragm 43. The diaphragm 43, moving in response to the difference in the pressure within the chamber and that of the atmosphere, controls the supply of operating fluid to the stoker engine 67 by the throttle 45 in the supply pipe 46 through the rod 44 attached rigidly to the diaphragm 43 and linked to the throttle 45.

At 47 I have illustrated a device which acts to vary the air pressure in the conduit 65 and in the master controller 68 in inverse ratio with the pressure of the steam in the header 64. A chamber 48 having a diaphragm 49 receives steam from the header 64 through the connecting pipe 50. A rod 51 is rigidly attached to the diaphragm and pushes upon a lever 52 hinged at 53. A weight 54 is partly suspended from the end of the lever 52 and partly supported by a rod 55 rigidly attached to a diaphragm 56. The diaphragm 56 closes one side of a chamber 57 in communication with the master controller 68 through the conduit 58. The position of the lever 52 determines the speed of an electric motor 59 which drives the blower 4 by adjusting the electrical resistance 60 through the pin 61 and sliding contact arm 62 in the motor circuit as shown.

The theory of the operation of the apparatus disclosed in Fig. 2 is similar in many respects to that given in connection with Fig. 1. At the point 63 there is a positive pressure corresponding to that at the point 11 of Fig. 1, from which point there will be a by-pass flow through the pipe 69, master controller 68, conduit 71 and branch 31 to the point 33 above the fuel bed 2. The pressure within the chamber 35 is that at a point along this by-path flow and the difference between this pressure and that of the atmosphere controls the position of the damper 6 and therefore the resistance to the flow through the furnace 1 offered by this damper. The damper 6 is controlled

therefore as is the damper 6 in Fig. 1, the valves 73 in the conduit 71 and 69^a in the pipe 69 corresponding to the valve 10 and the valve 32 corresponding to the valve 11 of Fig. 1. The negative pressure above the fuel bed is therefore controlled by the damper 6 to vary proportionately with the air duct pressure and as the pressure within the master controller 68 also varies with the air duct pressure it follows that the negative pressure at the point 33 above the fuel bed varies with the pressure in the master controller.

Similarly there will be a by-pass flow from the point 63 through the pipe 69, master controller 68, conduit 70 and branch 19 to the point 21. The pressure in the chamber 24 will be that at a point along this by-path flow and the difference between this pressure and that of the atmosphere will control the position of the damper 7 an increase in the pressure within the chamber tending to open the damper 7, to increase the draft suction. The increase in suction increases the negative pressure at the point 21 until the pressure within the chamber returns to that of the atmosphere. In the same way a decrease in the pressure within the chamber 24 results in a decrease in the draft suction, a decrease in the negative pressure at the point 21 and the consequent return to atmospheric pressure within the chamber 24.

The setting of the valves 69^a in the pipe 69, 73 in the conduit 70 and 20 in the branch 19 control the ratio between the positive pressure in the air duct or master controller and the negative pressure at the point 21.

The pressure within the chamber 42 is that at a point along the by-path flow from the point 63 through the pipe 69, controller 68, conduit 72 and branch 39 to the point of negative pressure 38 of the exhaust fan 37. The difference between this pressure and that of the atmosphere controls the flow of motive fluid through the valve 45 to the stoker engine 67 and therefore controls the speed of the stoker engine 67 and the speed of the fan 37 as well, an increase in the pressure within the chamber 42 causing the stoker to speed up and therefore the negative pressure at this point 38 to increase. The negative pressure at this point 38, and therefore the square of the speed of the stoker, is thus maintained proportional to the pressure in the air duct and so to the pressure in the master controller, the ratio depending upon the setting of the valves 69^a, 73, in the conduit 72 and 40 in the branch 39.

The pressures within the chambers 24, 35 and 42 are thus regulated to that of the atmosphere, variations from which pressure in any one of these chambers causing a movement of the damper or a change in the speed of the stoker, as the case may be, to return the pressure in the chamber to that of the atmosphere. The apparatus therefore operates to maintain at the points 21 and 33 within each

furnace negative pressures proportional to the air pressures delivered by the blower 4 to the air main 65 and master controller 68, and to maintain a stoker speed the square of which 5 is proportional to these air pressures. These air pressures are maintained inversely proportional to the steam pressure in the main header by the device 47 as already described, and the ratio between the pressure in the air 10 main and in the master controller can be adjusted manually at the master controller by means of the valve 69, and this ratio indicated by the gauges 18^a and 18^b. The ratio between the negative pressures at the points 15 21 of all the furnaces and that within the master controller may be adjusted by the valve 73 in the conduit 70. Similarly the valve 73 in the conduit 71 permits adjustment of the ratio between the negative pressures at the 20 points 33 of all the boilers and that within the master controller, and the valve 73 in the conduit 72 permits an adjustment of the ratio of stoker speeds to the pressure in the master controller. The valves 20, 32 and 40 permit 25 adjustment of these same ratios individually for each furnace or stoker, independently of the other furnaces or stokers.

When the regulating system is in operation 30 an increase in steam pressure in the main header, indicating a drop in load on the boilers, results in a decrease of the blower speed, a drop in the air supply main pressure, a drop in the pressure in the master controller, a decrease in the speed of the stokers, an initial 35 opening of the inlet dampers and a closing of the exhaust dampers to positions which will return the system to equilibrium at the new steam pressure. With a decrease in steam pressure the blower and stokers speed up, the inlet dampers tend to close and the outlet dampers to open to speed up combustion to correspond with the new load on the boilers. With constant steam pressure when 40 a change occurs in the fire bed, resulting in changed resistance to air flow, the changed pressure at the point 33 above the fuel bed will cause a corresponding change in the pressure within the chamber 35 and a shift in the position of the damper 6 to change its resistance to the air flow by an amount equal and 45 opposite to the change in the fuel bed resistance.

By using the air pressure from the common 50 forced draft air duct as the master controlling force I have eliminated the necessity for an auxiliary fluid pressure supply for this purpose and have thereby obviated one possible source of failure of the apparatus that has hitherto been inherent with the master controllers with which I am familiar.

It will be understood of course that the specific controlling means for the dampers and stoker speed illustrated in the figures are purely diagrammatic and indicate only that the controls are affected by a pressure responsive

device moving in response to the pressure of the atmosphere and to a pressure which is regulated to that of the atmosphere as a result of the element controlled. In practice the pressure responsive device illustrated as the 70 membrane 15 of Fig. 1 or the membrane 25, 36 or 43 of Fig. 2 would control an auxiliary apparatus operated by an external force such as oil pressure, compressed air or electricity, this auxiliary apparatus then supplying the 75 motive force to move the damper or to change the speed of the stoker. Such an auxiliary apparatus is shown in the drawing in my pending application, Serial No. 155,231 above referred to, and indicated by the numeral 11. 80

The specific device 47 of Fig. 2 is not essential to my present invention as any means for maintaining an air pressure inversely with the steam pressure might be employed, or, if desired, the air pressure could be maintained constant independently of the steam pressure. 85

I have now described and illustrated my invention as applied to the regulation of boiler furnaces, but I do not wish to be limited 90 beyond the scope of the annexed claims to such specific application, nor to the particular embodiments shown.

It is of course apparent that certain features of my invention might advantageously 95 be employed at times without the corresponding use of the other features and that many changes might be made in the arrangement of parts or in the elements controlled without departing from the scope of my invention. 100

I claim:

1. In a boiler furnace having an inlet damper, a stack damper, a stoker and a blower, a control system comprising in combination a master controller connected by pipe to the air duct of the blower, a conduit leading from the master controller to a point in the furnace just below the stack, a valve in said conduit at the point of connection to the master controller, and a second valve in said conduit near the far end thereof, means for controlling the stack damper by the differential between the pressure of the atmosphere and that at a point in said conduit intermediate said valves, a second conduit leading from the master controller and provided with a valve at the point of connection to the master controller, said second conduit leading to a point just above the fuel bed and likewise 120 provided with a valve near the far end thereof, means for controlling the inlet damper by the differential between the pressure of the atmosphere and that within said second conduit at a point intermediate the valves, an 125 exhaust fan operated by the stoker and varying in speed with the speed of the stoker, a third conduit leading from the master controller to the exhaust end of said fan and having one valve at the connection between the 130

master controller and this third conduit and a second valve near the far end of the conduit, means for controlling the speed of the stoker engine by the differential of the pressure of the atmosphere and that within the conduit at a point intermediate said valves, and means for varying the air duct pressure inversely with the steam pressure.

2. In a boiler plant comprising a plurality of boiler furnaces having regulable air and fuel supplies, a control system including in combination a master controller connected by pipe with the common air duct of the blower, means for causing a regulable by-path flow from said controller to a point in each furnace just below the stack, means for controlling the draft in each furnace in response to the differential of the pressure of the atmosphere and that at a point along said by-path flow, means for causing a regulable by-path flow from said controller to a point in each furnace just above the fuel bed, means for controlling the flow of air through the furnace in response to the differential of the pressure of the atmosphere and that at a point along said last mentioned by-path flow, means for creating a negative pressure proportional to the square of the speed with which the fuel is fed, means for causing a regulable by-path flow from the master controller to a point at such negative pressure, means for regulating the speed at which fuel is fed to the furnaces in response to the differential of the pressure of the atmosphere, and that at a point along said last mentioned by-path flow, means at the master controller for manually adjusting all of said by-path flows and means for varying the air duct pressure inversely with the pressure of the steam from all the boilers.

3. A steam generating furnace including an inlet damper, an outlet damper, a regulator for one of the dampers controlled in accordance with a desired intermediate between the pressure at a point in advance of the inlet damper and at a point beyond the furnace bed, and a regulator for the other damper controlled in accordance with a desired intermediate between the pressure at a point in advance of the inlet damper and a point near the outlet damper.

4. In a control system for boiler plants having a plurality of boiler furnaces the combination of a blower for producing a

forced draft, a device responsive to variations of steam pressure and to the pressure of the draft controlling the speed of the blower, individual combustion regulators for the several furnaces, and means for causing the variations of pressure of the draft to affect the control of each of the individual regulators.

5. A control system for boiler plants comprising in combination a master controller, means for supplying the master controller with a positive air pressure varying with the air duct pressure, means for creating a plurality of regulable air flows from said master controller to points of negative pressure, means for controlling an element effecting the combustion in a furnace by the differential between the pressure of the atmosphere and that at a point along each of said air flows, means at the master controller for adjusting each of said flows, and means for varying the air duct pressure inversely with the steam pressure.

6. In a control system for steam generating plants having a plurality of boiler furnaces, the combination of a blower for producing a forced draft, a plurality of individual combustion regulators at the several furnaces, a master controller for supplying air pressure to said individual regulators, means for supplying air under pressure from the blower to the master controller, and means for controlling the pressure of the air from the blower in accordance with variations of steam pressure.

7. A steam generating furnace including a blower and an inlet damper, a regulator for the damper and means for controlling said regulator in accordance with a desired intermediate between the pressure at a point in advance of the damper and at a point in the combustion chamber.

8. In a control system for steam generating plants having a plurality of boiler furnaces, the combination of a blower for producing a forced draft, a plurality of individual combustion regulators at the several furnaces, a master controller for supplying air pressure to said individual regulators, and means for supplying air under pressure from the blower to the master controller.

In testimony whereof, I have signed my name to this specification.

CHARLES H. SMOOT.
